DESIGN FOR A DRESS

Albert Ruchman, New York, N. Y.

Application April 14, 1939, Serial No. 84,288

Term of patent 3½ years

To all whom it may concern:

Be it known that, I, Albert Ruchman, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design;

Fig. 2 is the rear view thereof, and

Fig. 3 is an enlarged fragmentary view of the sleeve portion of the dress shown in Fig. 1 illustrating the beaded Schiffli appliquéd embroidery.

The instant design comprises a one piece dress of dotted fabric with a straight-cut top and a bias skirt cut on the straight, having a double row of flat, Schiffli embroidered flowers with contrastingly colored beaded centers appliquéd around the square neckline, a single row of matching appliqués around the sleeves, and a corsage on the sash at the natural waistline which matches the appliqués in type, the top being further ornamented by two tucks on each side of the neckline with corresponding tucks at the waistline giving a draped appearance to the blouse, all in combination on the specific dress as shown.

I claim:

The ornamental design for a dress, substantially as shown and described.

ALBERT RUCHMAN.
